UNITED STATES PATENT OFFICE.

BARNETT SHATZ, OF BUENOS AIRES, ARGENTINA, ASSIGNOR TO UNDERWOOD TYPEWRITER COMPANY, OF NEW YORK, N. Y., A CORPORATION OF DELAWARE.

TYPEWRITER-SPACING MECHANISM.

Application filed January 29, 1923. Serial No. 615,688.

To all whom it may concern:

Be it known that I, BARNETT SHATZ, a citizen of the United States, residing at Buenos Aires, Argentine Republic, have invented 5 certain new and useful Improvements in Typewriter-Spacing Mechanism, of which the following is a specification.

This invention relates to improvements in line-spacing mechanism for typewriters and 10 more particularly to improvements in the type of line-spacing mechanism disclosed in my Patent No. 1422892, July 18, 1922.

The primary object of the invention is to furnish a spacing-mechanism capable of very 15 minute adjustments so that the mechanism may be arranged to accommodate variously spaced lines on lined or ruled paper, and which will also permit the typewriter platen roll to be readily shifted to the proper position 20 for correcting the matter in a type-written line.

A further object of the invention is to provide a spacing-mechanism including friction contact elements adapted to positively 25 and instantaneously move the platen roll when the roll operating member is actuated.

Another object is to provide improved mechanism for locking the adjustable stop of the shifting mechanism in various positions. 30

A still further object is to provide a novel resilient washer locked in position and functioning to hold the platen shaft operating disk in a fixed position relatively to the 35 pawls or cams with which it co-operates.

With the foregoing objects outlined and with other objects in view which will appear as the description proceeds, the invention consists in the novel features described in detail, illustrated in the accompanying drawing and more particularly pointed out in the appended claims.

Referring to the drawing:

Figure 1 is an end view of a portion of a 45 typewriter carriage with my improvements applied thereto.

Fig. 2 is a vertical sectional view of certain of the details.

Fig. 3 is a top plan view of the parts 50 shown in Fig. 1.

Fig. 4 is an end view partly in section of the resilient washer employed for forcing the friction disk and platen shaft in a certain direction.

55 In the drawing, 1 designates a bell crank

lever pivotally mounted on the shaft 2 of the platen roll of the machine and provided with a pointer 3 at its upper end cooperating with a graduated scale 22 arranged horizontally on one of the end plates 23 of the typewriter carriage. The upwardly extending arm of the bell crank lever is provided with a screw or the like 4 forming a pivot for the cam pawl 5 having a tail-piece 5^a provided with an abutment surface *x*. 60

The bell crank lever 1 is held in a normal position by means of a spring 6 having its lower end connected to the arm 1^a of the bell crank lever and its upper end secured at 6^a to the end plate 23 of the carriage frame. 65

This spring draws the arm 1^a of the bell crank lever upwardly and causes the shelf 1^b of said arm to abut against the lower end of the stop screw 9. This stop screw extends through a split stationary nut 7, which is secured to the end plate 23 by means of the screw 8. The stop screw 9 has a head 10 adapted to be engaged by the operator for adjusting said screw. The split portion of the nut 7 is provided with a thumb-screw 11 70

adapted to contract said split nut for locking the screw 9 in position. The end plate 23 is provided with a depending lug 13 which is apertured to form a bearing for the sliding bar 12, which is provided at its forward end with an angular portion 15 adapted to be depressed by the operator for causing actuation of the mechanism. A bearing-lug 14 also slidably supports said bar 12. 75

The bar 12 is moved forwardly by a spring 16 which has one of its ends fixed to a screw 17 on the end plate 23 and its other end secured at 18 to the rear end of the bar 12. A screw 16^a limits the forward movement of the bar 12. 80

The sliding bar 12 is provided with a pin 19 adapted when the sliding bar is moved rearwardly to strike the abutment surface *x* and cause the cam pawl 5 to swing about its axis 4. This causes the periphery of the cam to frictionally lock with the disk 21 which is keyed to the shaft 2 at 21^a. When the cam 5 locks itself to the disk 21, said disk will turn in a counter-clockwise direction with the bell crank lever 1 and this movement will continue until a second cam pawl 5^b mounted on the arm 1^a of the bell crank lever, strikes a stop element 5^c. When this occurs the cam 5^b will be also swung into a position to lock itself against the periphery 100

110

of the disk 21, and then the bell crank lever 1, pawls 5^a and 5^b, disk 21 and the platen shaft 2 will all move together. The provision of two cams at substantially opposite sides of said disk 21 insures positive locking between the bell crank lever and the disk 21 so that there will be no slippage liable to cause inaccuracies.

In order to force the disk 21 toward the left so that it will occupy a position to be engaged by the pawls, I have provided a resilient cross-shaped washer 23^a which is mounted on the shaft 2 and bears at one side against a washer 24 and at its other side against the disk 21. One arm of said washer is elongated and provided with an aperture, as shown in Figure 4, to receive a pin 25 which is fixed to the end plate 23. This prevents the washer from rotating with the disk 21.

In operation, the thumb-screw 11 is loosened and the screw 10 is adjusted. If the screw 9 is moved downwardly its end will rock the bell crank lever in a counter-clockwise direction and the pointer 3 may be brought to a proper position relatively to the marks on the scale 22. If the screw 10 is moved upwardly, the spring 6 will cause the bell crank lever to move in a clockwise direction and follow the screw 9. When the pointer 3 is brought to a proper position to accord with the spacing desired, the thumb screw 11 is tightened and this will cause the screw 9 to remain indefinitely in its fixed position. Then the platen roll may be advanced step by step to accord with the spacing desired, by depressing the operating bar 12 to move the same toward the left or rearwardly. As the bar moves rearwardly its pin 19 causes the pawl 5 to swing in a counter-clockwise direction and lock on the disk 21. Continued rearward movement of the bar 12 causes the cam 5, bell crank lever 1 and disk 21 to move together until the pawl 5^b engages the stop 5^c, and then said pawl 5^b will lock on the disk and also move with the same. The movement of the bar 12 will be continued rearwardly by the operator until the platen roll has been advanced the desired amount, and then the bar 12 is released and the spring 16 will automatically return the same to its initial position, while the spring 6 will return the bell crank lever and its connected parts to normal position. A spring 20 is provided for holding the cam 5 normally in a position where it will not interfere with the rotation of the disk 21 independently of the bell crank lever, so that said platen shaft may be actuated without disturbing the line-spacing mechanism.

Prior to the present invention it has been proposed to provide the platen shaft with a ratchet wheel having fine teeth adapted to be engaged by pawls, but it has been found

by actual practice that the spaces between such teeth become clogged and after short use the spacing-mechanism becomes inaccurate.

From the foregoing it is believed that the construction, operation and advantages of the invention may be readily understood and it is apparent that various changes may be made in the details disclosed without departing from the spirit of the invention as expressed in the claims.

What I claim and desire to secure by Letters-Patent is:

1. The combination with a platen shaft, of a friction disk mounted on the same, a cam pawl adapted to lock with said disk, means for swinging said cam about its axis to cause the cam to lock with said disk, and means, including a second cam pawl acting on said disk, for holding the cam in a fixed position relatively to said disk after the cam has been locked to the disk. 80

2. In a typewriting machine, a platen shaft, a disk fixed to said shaft, a lever movable about the axis of said shaft, a cam pawl carried by said lever, an operating member engageable with said cam pawl for swinging the latter about its axis and causing the same to lock on said disk, and a second cam pawl pivoted to said lever and also 90 engaging said disk to lock the lever thereto. 95

3. In a typewriting machine, a platen shaft, a disk fixed to said shaft, a lever pivotally mounted on said shaft, a cam pawl carried by said lever and adapted when swung in one direction to lock on said disk, an operating member adapted to swing the cam in its locking direction and then cause the cam and lever to swing about the axis of said shaft, a second cam pawl pivoted to 100 said lever and also engaging said disk to lock the lever thereto, and means for returning said lever to its initial position. 105

4. In a typewriting machine, the combination with a platen shaft, of a friction disk fixed to said shaft, a lever pivotally mounted on said shaft, a cam pawl pivotally mounted on the lever and adapted when moved in one direction to lock itself to the disk, an operating member for swinging said cam into its locking position and for then causing the pawl and lever to move said disk, a second cam pawl pivoted to said lever and also 110 engaging said disk to lock the lever thereto, and a spring for returning said lever to its initial position. 115

5. In a typewriting machine, a platen shaft, a disk fixed to said shaft, a lever pivotally mounted on said shaft, a locking member arranged on said lever and adapted to 120 lock itself to said disk, an operating member for moving said lever in one direction, a stop screw for adjusting said lever, a split stationary nut engaging said screw, and a second screw adapted to contract said split 125 130

nut for locking the first mentioned screw in adjusted positions.

6. A typewriting machine as claimed in claim 1 including a resilient washer mounted 5 on the shaft and engaging the disk for yieldingly forcing the same in one direction, and means for locking said washer in position to prevent the same from turning with said disk.
- 10 7. In a typewriting machine, a carriage end plate, a platen shaft extending through said end plate, a disk fixed to said shaft and provided with a smooth periphery, a double armed lever pivotally mounted on said shaft 15 and provided with a plurality of pivotally mounted cam pawls adapted when swung in certain directions to lock themselves to said disk, a slidible operating bar provided with a pin adapted to engage one of said cam pawls for swinging the same into locking 20 position, a fixed stop member adapted to engage the other pawl for swinging the same into locked position, a spring engaging one arm of said lever and functioning to swing the lever in one direction, and an adjustable 25 stop engageable with said lever for limiting its movement in one direction.

In testimony whereof I hereunto affix my signature.

BARNETT SHATZ.
